UNITED STATES PATENT OFFICE.

RALPH A. LIGHT AND JOSEPH W. PRICE, JR., OF PHILADELPHIA, PENNSYLVANIA,
ASSIGNORS TO THE UNITED STATES METALLIC PACKING COMPANY, OF PHILA-
DELPHIA, PENNSYLVANIA, A CORPORATION OF PENNSYLVANIA.

BORING TOOL FOR METALLIC PACKING RINGS.

Application filed December 23, 1922. Serial No. 608,708.

To all whom it may concern:

Be it known that we, RALPH A. LIGHT and JOSEPH W. PRICE, Jr., citizens of the United States of America, and residents of Philadelphia, in the county of Philadelphia, in the State of Pennsylvania, have invented certain new and useful Improvements in Boring Tools for Metallic Packing Rings, of which the following is a true and exact 10 description, reference being had to the accompanying drawings, which form a part thereof.

Our invention relates to the construction of a boring tool especially adapted for use 15 in boring out metallic packing rings such as are used in connection with piston rods and valve stems. The object of our invention is to provide a tool especially adapted for this service and the nature of our improvements will be best understood as described in connection with the drawings in which—

Figure 1 is a sectional elevation of our tool, and

Figure 2, a cross sectional elevation taken on the line 2—2 of Fig. 1, looking toward the left.

A indicates the base plate of the frame of the machine having an upwardly extending web A' and substantial upwardly extending arms B, B', which support bearings for the shaft of the boring tool. The left hand arm B is further provided with an annular flange C continued as a cylinder C' from which again continues the ring receiving chuck formed, as shown, of a conical section C² merging into a cylindrical section C³ which is externally threaded, as shown, and on which screws the clamping ring indicated at D. This construction provides inside of the chuck C², C³, a chamber C⁴ in the lower portion of which is formed an opening C⁵ for the escape of chips. E and E' indicate the bearings secured in the arms B, B'. F and F' are arms extending out from the arms B, B', and supporting a rod F² which is pressed through a perforation in the arm F' into a socket in the arm F and secured in place by a plug 45 and set screw, as indicated at F³.

G is the shaft of the machine supported

and turning in the bearings E, E', having a reduced section G' to which is attached the boring tool H, H' indicating a screw for clamping the tool in place. To the opposite end of the shaft G is secured the hand wheel indicated at I. An intermediate portion G² of the shaft G is reduced in diameter, as shown, and this reduced portion has conical shoulders at each end, as indicated at G³, G⁴. J is an arm secured to the shaft F² and having a threaded portion J² which fits on the threaded section G² of the shaft. The arm A is provided with a handle J' by which it can be lifted when desired.

In operation a packing ring is secured in the chuck by means of the clamping ring D and the arm J being engaged through its threaded portion J² with a threaded portion G² of the shaft, the shaft is rotated with the result that the cutting tool H is rotated and, at the same time, moved longitudinally. Continued rotation of the shaft in either direction brings the jaws of the arm J into contact with the conical shoulders G³ which lift the arm J out of contact with the threaded portion of the shaft and, of course, arrests the longitudinal movement of the shaft and tool.

Having now described our invention, what we claim as new and desire to secure by Letters Patent, is:

A boring tool for metallic packing rings, comprising a frame having spaced arms in combination with shaft bearing supported in said arms, a ring holding chuck supported on the outside of one arm, a tool holding shaft rotatably and longitudinally supported in the bearings, said shaft having an intermediate portion reduced in diameter and screw threaded and formed with beveled surfaces connecting the ends of the reduced portion with the surface of the shaft and a segmental nut supported on the frame and movable towards and away from the shaft, said nut normally engaging the threaded portion of the shaft and being disengaged therefrom by the bevels at the ends of the reduced and threaded portion of the shaft.

RALPH A. LIGHT.
JOS. W. PRICE, JR.
